APPARATUS FOR COATING FLUORESCENT LAMPS

August E. Kulberg and Charles L. Albright, Beverly, Mass., assignors to Sylvania Electric Products Inc., a corporation of Massachusetts

Application September 4, 1941, Serial No. 409,497

1 Claim. (Cl. 91—43)

This invention relates to fluorescent lamps and, more particularly to apparatus for applying a coating of luminescent material thereto.

An object of this invention is to provide an apparatus which will give a smooth even coating of luminescent material on the walls of the elongated tubular glass envelopes.

Another object is to provide an apparatus which will insure a coating free from streaks.

A further object is to provide an apparatus capable of withstanding the harsh abrasive effects of the luminescent material.

Further objects, advantages and features will be apparent from the following specification taken in conjunction with the accompanying drawing in which:

Figure 1 is a side elevational view of the bulb coating apparatus.

Figure 2 is a detail partly in section of the valve assembly.

Figure 3 is a detail partly in section of the nozzle assembly.

In Figure 1, the bulb 1 is placed in position beneath the flushing nozzle 2, the lower extension of the bulb resting flush within the guide 3. The control handle 4 is located directly behind the bulb 1, so that the operator may, almost simultaneously and with the same hand, position the bulb and set the coating apparatus into operation by pulling the handle 4 forward.

When the handle 4 of the rocker 5, held through the pin 6, is drawn forward it causes the arm 7, connected to the rocker 5 through the pin 8 to move upwardly.

The arm 9 is pivotally mounted on the supporting plate 10 extending from the pipe 11. This arm 9 pivots at its longitudinal center about the stud 12. An end of arm 7 is connected to one end of arm 9 and an end of arm 13 is connected to the other end thereof. Thus the upward movement of the arm 7 is transmitted through the arm 9 into the downward movement of the arm 13. The arm 14 is connected to the arm 13 through the pin 34 and is pivotally mounted on the top of the valve 15 through the stud 33. The downward movement of the arm 13 results in the yoke of the arm 14 moving upward and thereby opening the valve 15 through which the luminescent solution flows.

The rod 16 extends from within the valve 15 up to the arm 17. The collar 21 is fixed to the rod 16. The rod 16 passes through the yoke of the arm 14. Thus when the yoke of the arm 14 moves upward, it pushes upward the collar 21 and the rod 16 to which it is attached. Inasmuch

as the arm 17 pivots about stud 18 on the supporting plate 19, the upward movement of the end of the arm 17 adjacent the rod 16 will result in the downward movement of the other end thereof. This in turn pushes the rod 20 downward. This rod 20 extends down into the nozzle 2 and its downward movement opens the nozzle and permits the luminescent solution to flow therefrom.

Provision has been made on this apparatus to cause the above-described mechanism to return to its normal position when the operator releases the handle 4 after the tube 1 has been sufficiently coated. It is highly desirable to have the valve 15 closed to prevent any more luminescent solution from flowing therethrough and to have the nozzle 2 closed to prevent loss of luminescent material therefrom after the bulb 1 has been removed. To this end, the arm 21 has been fixed to the upper extremity of the rod 16 and a pair of springs 22 suspended between this rod and the top of the valve 15. The upward movement of the rod 16 will set up a tension on the springs 22. As soon as the operator releases the handle 4 the tension will expand itself, the springs returning to their normal position and thereby pushing the rod 16 downwardly to close the valve 15.

The downward movement of the rod 20 which permits the flow of luminescent solution from the nozzle 2 causes the compression of the spring 23 which is concentric with the rod 20 and located between the top of the nozzle 2 and the collar 24 fixed on the rod 20. Thus when the operator releases the handle 4, the compressed spring 23 will expand, thereby pushing the rod 20 upward by reason of the fact that collar 24 is attached thereto. In this way, the nozzle is effectively closed to prevent any further flow of coating solution therefrom.

Figure 2 shows the internal structure of the valve 15 and Figure 3 shows the internal structure of the nozzle 2. It should be noted that both employ a metallic bellows in its internal structure. This structure has been found highly advantageous in eliminating bearing contact whenever possible due to the highly abrasive nature of the luminescent solution.

In Figure 2, the top of the bellows 25 is fixed to a collar 26 located beneath the cap of the valve 15 through which the rod 16 extends. The bottom of the bellows 25 is attached to the collar 27 which is fixed to the rod 16. The disc 28 is located on the bottom of the rod 16 and it is the raising and lowering of this disc that controls the flow of the luminescent solution through the

valve. Thus it may be seen from this structure that bearing contact of moving parts with luminescent solution is eliminated. The movement of the rod 16 to open and close the passage of solution through the valve 15 is completely enclosed by the bellows at the point of contact.

In Figure 3, the bellows 29 is fitted within the nozzle 2 in a manner similar to that in which the bellows 25 is fitted within the valve 15. The solution deflector plug 30 on the end of the rod 20 is normally closed with the opening in the bottom of the nozzle 2 thereby preventing any coating solution flowing therefrom. When the operator draws forward the handle 4 as shown in Figure 1, the rod 20 is pushed downward, thereby causing the solution deflector plug 30 to move out from the opening in the bottom of the nozzle 2 and to permit the luminescent solution to flow therefrom.

The movement of the rod 20 within the nozzle 2 is never such that a bearing contact is exposed to the coating solution for the rod 20 is enclosed within the bellows 29. This bellows 29 is fixed at both its ends, the top to the collar 31 and the

bottom to the collar 32. Thus, like bellows 25 in Figure 2, it expands and contracts with the movement of the rod 20.

What we claim is:

5 A valve unit for coating glass tubes with luminescent material, said unit comprising: a conduit for carrying said material; a control valve adjacent the end of said conduit; a delivery valve at the end of said conduit; means on said delivery valve for receiving an end of a tube to be coated; a guide member below said delivery valve, for aligning a tube with an end in said delivery valve receiving means; a linkage system arranged to operate said valves simultaneously; and a handle 10 for operating said valves through said linkage, said handle being pivotally mounted adjacent said guide member whereby a tube, as arranged for coating in said unit, may be included in a manual grip on said handle, and pressed against said guide thereby, as a fixed member in the contraction of said grip to pivot said handle and operate said linkage.

AUGUST E. KULBERG.
CHARLES L. ALBRIGHT.
